CIGARETTE REST FOR AN ASH TRAY OR SIMILAR ARTICLE

Robert G. Peter and Clement M. Kucera, Houston, Tex.

Application August 29, 1955, Serial No. 37,695

Term of patent 3½ years

(Cl. D85—2)

Figure 1 is a perspective view of a cigarette rest for an ash tray or similar article, showing our new design.

Figure 2 is a side elevation view of a cigarette rest for an ash tray or similar article.

The broken line showing of an ash tray is for illustrative purposes only.

We claim:

The ornamental design for a cigarette rest for an ash tray or similar article, as shown and described.
